UNITED STATES PATENT OFFICE.

ORVILLE C. HATCH, OF SEATTLE, WASHINGTON.

AIR-HEATING-CONTROL SYSTEM.

Application filed March 14, 1925. Serial No. 15,527.

My invention relates to controlling systems as applied to air-heating systems of buildings, wherein a forced circulation is used, and where supply to the radiators is capable of being drawn either from the interior of the building or from without the same, and in which the circulation during the preliminary stages of getting up to the desired temperature is taken from within the building, and thereafter in whole or in part from without the building.

The object of my invention is to provide a means for automatic control of all of the various dampers which it is essential to employ, whereby the inlet dampers, when the system is in cooled condition are set so as to cut off the supply of air from the outside of the building and to draw the same entirely from within the building until a certain temperature of the rooms being heated has been reached, and thereafter to operate with the supply drawn from the outside air and also to exercise a second control which affects the amount of air passed through the radiator, and thereby the amount of heat added to the air in the room, the whole being done automatically.

My invention consists in so coupling all of the various dampers employed in controlling the air circulation, that they may be effectively controlled entirely from and by the thermostat control mechanism which has previously been employed for controlling the temperature of the room.

In the accompanying drawings I have shown my invention in a somewhat diagrammatic manner, but sufficiently to illustrate the principles thereof and the manner of applying them.

Figure 1 shows in a diagrammatic manner the elements entering into the system.

Figure 2 shows in partial section the manner of connecting the various dampers and the automatic control means therefor.

In what is known in the trade as the unit-heating system, it is customary to employ a radiator which is enclosed within a casing or chamber and provided with partitions or other means whereby the air circulated in the room is passed either wholly or in part through the radiator to be heated, or through another passage about the radiator, whereby the air so by-passed will not be heated by the radiator. Such devices are in common use and the damper which controls the dis-

tribution of the air to the radiator or through the by-pass, is automatically controlled by a thermostatically-actuated mechanism located somewhere in the room. In connection with such apparatus it is common to employ two inlet or supply valves or dampers one communicating with and drawing its supply from the room or other interior of the building, and the other communicating with and drawing its supply from without the building.

In the operation of such a device the two inlet dampers are, or may be, connected to be operated together, but so far as I am aware these have been operated to shift the source of supply as between the interior and exterior of the building by hand. By my invention these are connected up with the same means employed to control the distributing damper so as to be operated thereby but in advance of the distributing damper, whereby the distributing damper is not open to by-pass the circulated air until the temperature as affecting the thermostat has reached a certain point.

In the device illustrated in Figure 1, 1 represents a casing in which is mounted a radiator 10, supplied with steam or other heating agent through pipes 11 and 12. In this same casing, or in a chamber communicating therewith, is located a motor 13 having a fan or fans 14 operated thereby, whereby a forced circulation of air is produced.

In connection with an accepted and commonly used type of thermostat, of which one is represented at 2, a pressure air operating system is employed. This, as illustrated employs a compressor 20, operated from a motor 21, an air storage tank 22 and pipes 23 and 24, one leading from the storage tank to the thermostat, and the other discharging the air.

The air discharged from the thermostat is conducted to the mechanism which is employed for controlling the dampers. Such a mechanism is illustrated in Figure 2. This may, and preferably is, included in or associated with the casing which contains the radiator. This casing has a damper 3 located so as to control a by-pass passage 30, whereby the air being circulated may be caused to either pass through the radiator or to pass by the radiator without being heated. Two inlets for air are shown at the bottom of this casing. One of these

is controlled by the damper 4 and the other by the damper 5. One of these, assumed to be the damper 4, controls the air as it may be drawn from without the building, and the other, as 5, controls the air which may be drawn from within the building. These are connected as by links 40 and 50 so as to be operated together but in inverse relation, one opening as the other closes. In the construction illustrated these two links are connected with a lever as 6, pivoted at 60, and actuating a rod 61 which enters a casting 62 of the device by which the power is applied to the dampers to control them. This device may be any kind of a piston and cylinder device which is capable of movement under variations of air pressure. The lever 6 is drawn in one direction by a spring 63 or by any equivalent means. The operating air is delivered to the mechanisms through the pipe 24. A similar device is shown as applied to the distributing damper 3. The construction of this is slightly different, although the principles are the same.

It is evident that if air under pressure be introduced to the cylinder or chamber 62 and if the piston in this chamber be a diaphragm, such diaphragm, or an equivalent piston if one be employed, will be moved against the action of the spring 63, the extent of the movement depending upon the intensity of the pressure. Such movement will, through the connecting mechanisms described, swing the dampers. When, however, the pressure in the cylinder is reduced, the spring will cause the diaphragm to move backward and the dampers are swung in an opposite direction.

In connection with one or both of these pressure-operated controlling means, I provide means for adjusting the tension of the spring. Such means as illustrated in Figure 2, consist of a nut 64 threaded upon a stem 65 passing through the spring so as to adjust the initial tension of the spring. It is evident that if the spring of the device controlling the distributing damper 3 be adjusted so as to require a higher pressure to operate it so as to open the damper 3 thereby to by-pass air about the radiator, than that required for operating the device which controls the inlet dampers 4 and 5, said inlet dampers, will be operated so as to close that one which draws air from within the room and open that one which draws air from without the building, prior to the action of the distributing damper 3. This being the case, the distributing damper 3 will be held into the position such that all of the air is passed through the radiator before the inlet dampers are set so as to draw the supply from outside, and thereafter the distributing damper will be adjusted so as to control the amount of the

circulated air which passes through the radiator, and thereby control the heat in the room.

By connecting the supply dampers in this manner so as to be controlled automatically from the thermostat which is now employed in the room, it will be unnecessary to manually attend to the shifting of the inlet dampers. This will avoid the necessity of having control mechanisms from the various unit heating devices running to a central station or to dispense with the movement of any person around to a number of such unit heating systems to shift the damper at the time required. This work is also thus done automatically and when the temperature is right, whereas if the change is done manually it is liable in most cases to be done a little too early or a little too late. Also, when a number of rooms are connected so that the change is made simultaneously from a central station, it is likely to be done in many rooms before they become properly heated, and not to be done in other rooms until after they have become over-heated. The system here proposed, while saving labor, accomplishes to greater perfection the equitable control of the heat.

The successive operation of the two sets of dampers may be secured by varying the areas of the diaphragms or pistons which control the dampers. By making the area of the diaphragm which controls the inlet dampers larger than the area of the diaphragm which controls the distributing damper, the inlet dampers will be shifted in advance of the distributing damper when the springs of the two have equal effect. Varying the diaphragm or piston area is broadly an equivalent of varying the spring tension.

While I have shown two dampers controlling the inlet openings and one distributing damper, it is evident that a single damper or a double damper may be used at either place, or the arrangement may be reversed from that shown.

What I claim as my invention is:

1. In a unit heating and ventilating system, the combination of a casing provided with an outlet opening and inlet openings communicating with different sources of air supply, dampers controlling said inlet openings and operatively connected together whereby one is opened as the other is closed, a radiator in said casing, and a by-passage between said inlet openings and said outlet, a damper for controlling the passage of air through said by-passage, and thermostatic apparatus connected with said inlet and by-pass dampers and adapted to be adjusted to actuate said dampers successively at a predetermined temperature of the space to be heated and ventilated.

2. In a unit heating and ventilating sys-

- tem, the combination of a casing having an air outlet and air inlets communicating with different sources of air supply, a radiator in said housing between said inlet and outlet, 5 a damper in said housing arranged to by-pass the air around said radiator, dampers controlling said inlet openings, thermostatic mechanism connecting said inlet dampers to simultaneously open one and close the other, 10 and separate thermostatic mechanism connected with said by-pass damper and adjusted to operate at a different temperature condition than said inlet damper mechanism. 15 3. In a unit heating and ventilating system, the combination of a casing, having connected recirculating and fresh air inlet dampers, a radiator in said casing, and an outlet beyond said radiator, a by-pass 20 damper in said casing adapted to control the passage of air through or around said radiator, separate thermostatic devices connected with said inlet and by-pass dampers, having a common source of air pressure, one 25 of said thermostatic devices being adjusted to function at a different pressure. 4. In a heating and ventilating unit, the combination of a casing having inlet openings communicating with different sources 30 of air supply and an air outlet, a radiator in said casing between said inlet and outlet
- openings, a by-pass damper operative to direct all or part of the air from either of said inlets through said radiator, thermostatic mechanism for operating said inlet dampers 35 simultaneously to open one and close the other, and separate thermostatic mechanism connected with said by-pass, said mechanisms being operated from a common source of air pressure, and the latter adjusted to 40 function at a different pressure. 5. In a unit heating system, a radiator and a casing therefor having passages directing the circulated air either through the radiator or to by-pass the radiator, a distributing damper controlling the disposition of the air passing the radiator, two inlet 45 dampers controlling the supply of air being circulated, one communicating with the building interior and the other with the outside air, two fluid pressure actuated controlling means, one connected with the two inlet dampers to move them oppositely and the other with the distributing damper, the latter controlling means being adjusted to work 50 at a higher pressure than the former, and a common pressure air supply to both of said controlling means.
- Signed at Seattle, King County, Washington, this 25th day of February, 1925.

ORVILLE C. HATCH.
